BUCKLE

Harry P. Troendly and Paul W. White, Chicago,
Ill., assignors to Parva Products Company,
Chicago, Ill., a corporation of Delaware

Application December 7, 1934, Serial No. 756,534

8 Claims. (Cl. 24—73)

This invention relates to a buckle and has a special reference to a buckle adapted to be adjustably associated with straps, bands and the like, for the support of garments or other objects on the person.

More particularly, this invention relates to a slide buckle formed of a single piece of sheet metal constituting a frame which comprises side bars and three spaced cross bars connecting the side bars, the central cross bar being resiliently secured to the side bars and being provided with a gripping portion that subtends in close proximity a major portion of the top bar to form a slot through which a strap, band or the like is threaded and gripped and to form an open slot adjacent to the lower bar for receiving the free end of the strap. It is preferable to provide the lower cross bar with an outwardly extending button loop having a passage leading to the open slot adjacent the lower bar for receiving a button of a garment or the like to be supported, the passage being of sufficient width to permit the shank of the button to pass therethrough into the button loop.

It is contemplated by the present invention to adopt this construction for use with various types of objects, particularly on the person. However, in the drawing and in the following description, the buckle will be shown and described in connection with a shoulder strap of an overall, the strap being threaded through the upper slot and passing downwardly through the lower slot with the free end pointing downwardly. It is readily apparent, of course, that various other uses could be mentioned in connection with buckles and fasteners generally of the type adapted to be adjustably associated with straps and that this invention, therefore, is not to be limited to the specific use herein described and illustrated.

In a buckle of the above noted type, it is highly desirable to provide for the utmost simplicity in the threading of the strap through the buckle, to provide an ease in the adjustment of the strap through the buckle when in use on the wearer and to provide that the free end of the strap points downwardly. In the present invention, the arrangement and nature of the two slots and the flexibility of the gripping means cooperate to accomplish the above desired results. Further, the construction and arrangement of the elements of the buckle are such as to minimize the weight and expense from a standpoint of material used. The overall measurement and weight of the buckle provide a material savings in plating, packing, freight, storage and shop handling cost in comparison with present commercially exploited

stamped buckles of the same type or for use on the same sized strap.

In order to minimize the length of the buckle and yet maintain all of the properties in the usual type of stamped buckles, the lower bar is provided with a button loop portion which has a passage leading to the open slot for receiving a button of a garment or the like to be supported. The central resiliently connected bar provides a relatively high flexibility of the strap engaging and gripping portion, a portion of the flexible bar acting in a manner to back up the strap which encloses one side of the button loop. The cloth may be pushed back and the flexible bar may yield, and because of the particularly desirable spring properties, a very easy manual engagement and disengagement of the button is had. This further provides a condition such that the button may never become displaced by wear in any use or condition thereof.

The resiliently connected central bar permits easy threading and a very positive grip on the strap by reason of the long effective length of the supporting arms which are preferably tortuous in their length and yield mainly in torsion, they further being of narrow width for yielding very readily. These arms are preferably crowned or of arcuate cross section whereby the resistance to torsion yielding is not increased but strength is added greatly in all other directions of flexure. The central resilient cross bar is very flexible in the direction toward and away from the upper cooperating cross bar so that it may be flexed open readily for threading or closed just as readily for locking upon the exertion upon a relative pull between the strap and the frame. However, it is very rigid in the other direction or at the right angles to the direction of movement or flexing of the central bar, because in this direction it must assume a large portion of the pull on the strap when the strap is stretched taut or jerked as is very often the case.

The present buckle is preferably formed of a comparatively thin, spring material into which has been imparted high physical properties by thermal heat treatment after all forming operations involved have been completed. While we will herein treat of a very desired material in relation to its thickness as compared to its width of strap opening and its thermal heat treatment, we will reserve the right to file a separate application thereon in which will be claimed the physical properties of the buckle in the present application. We are interested primarily in the structural characteristics of the buckle in the present

application aside from the physical properties and dimensions of the buckle itself.

One of the objects of this invention is to provide a buckle of the character indicated above in which it is comparatively easy to thread a strap, in which it is easy to adjust the strap after it is threaded therein and while on a wearer, in which a loose end of the strap points downwardly when in use on the wearer and which is of a minimum weight and size to be less expensive in plating, packing, freight, storage and from the standpoint of material used in the making of the buckle.

Another object of this invention is to provide a buckle of the type above noted which is formed of a single sheet of metal having an outer frame and a resiliently connected tongue, the tongue having a gripping portion which subtends a major portion of one bar and provides upper and lower strap openings to receive a strap threaded therethrough, the lower slot communicating with a button loop.

Other objects and advantages will hereinafter be more particularly pointed out, and for a more complete understanding of the characteristic features of this invention, reference may now be had to the following description when read together with the accompanying drawing, in which latter:

Figure 1 is a front elevational view of a buckle incorporating the features of this invention;

Fig. 2 is a front elevational view of the buckle of Fig. 1 showing it in position on fragmentary portions of a strap and an overall bib;

Fig. 3 is an enlarged central vertical sectional view taken on the line 3—3 of Fig. 1;

Fig. 4 is an enlarged substantially central vertical sectional view taken on the line 4—4 of Fig. 2;

Fig. 5 is an enlarged vertical sectional view taken on the line 5—5 of Fig. 1;

Fig. 6 is a front elevational view of a modified form of buckle incorporating the features of this invention;

Fig. 7 is an enlarged vertical central sectional view taken on the line 7—7 of Fig. 6;

Fig. 8 is an enlarged vertical sectional view taken on the line 8—8 of Fig. 6;

Fig. 9 is a front elevational view of another modified form of buckle embodying the features of this invention;

Fig. 10 is an enlarged central vertical sectional view taken on the line 10—10 of Fig. 9;

Fig. 11 is a front elevational view of a still further modified form of buckle embodying the features of this invention, the buckle being shown in an incomplete state of manufacture or during a forming operation thereof;

Fig. 12 is a sectional view taken on the line 12—12 of Fig. 11;

Fig. 13 is a view similar to Fig. 11 showing a changed position of the gripping bar, the buckle being shown in the completed state; and

Fig. 14 is a vertical sectional view taken on the line 14—14 of Fig. 13.

Referring now to the drawing and more particularly to Figs. 1 to 5, inclusive thereof, the buckle of this invention comprises a frame preferably crowned along the outer confines and having side bars 15 and 16 and three spaced cross bars 17, 18 and 19 connecting the side bars 15 and 16. The buckle is formed of a single piece of sheet metal with the central cross bar 18 being resiliently connected to the side bars and being formed from the material within the confines of the frame.

The central cross bar 18 has a tongue or gripping portion 20 that subtends in close proximity

a major portion of the length of the top cross bar 17 to form an upper slot through which a strap 20a may be threaded and gripped. The tongue 20 and the cross bar 17 preferably overlap each other for at least a portion of their subtending areas as by means of extruding a portion of the material of the cross bar 17 in any desirable manner, such as is shown at 21 in Figs. 1 and 5. Of course, it is to be understood that an overlapping relation may be had by extruding a portion of the material of the tongue 20 in the same manner as that of the extruded portions of the bar 17. This overlapping relation limits the movement of the resiliently secured cross bar 18 in one direction, that is, toward the cross bar 17.

The tongue 20 is preferably provided with arms 22 and 23 oppositely extending from the tongue to resiliently secure the central cross bar 18 to the side bars and the points at which the arms 22 are attached to the side bars are preferably spaced from the upper cross bar 17 a distance slightly greater than the thickness of the strap. Further, the arms are preferably tortuous in the direction of their length, narrow in width and arcuate or crowned in cross section so that the tongue 20 may be very flexible in its direction to and from the upper cross bar 17 to open for threading and to close for locking or gripping and still be very rigid in the direction of the plane of the frame, because in this latter direction it must assume a large portion of the load upon the strap and the exertion of a relative pull or jerk between the strap and the frame. It is, of course, to be understood that a satisfactory buckle may be had in the use of the arms and tongue in a flat condition although added strength is given against the load with substantially the same flexibility in a crowned condition of the arms and tongue.

In providing a tortuous length to the arms, an initial portion, as above noted, spaced a distance slightly greater than the thickness of the strap, extends inwardly in a direction toward the tongue to substantially the ends of the tongue portions where it may bend in a direction downwardly and then inwardly again to form an open slot 24 with the lower cross bar 19. The lower open slot 24, in turn, is preferably substantially the width of an average strap (approximately $\frac{3}{2}''$) to prevent the free end of the strap from creeping upwardly and out of the slot during normal use of the buckle on the wearer.

Further, it is desirable in order to assure a very flexible gripping portion that the central bar opposite to the lower bar be provided with a recess opening into the lower slot to form a continuation of the arm 22 extending in opposite directions and outwardly to be connected preferably with the outer extremities of the gripping portion 20 of the central bar, the arms being narrow in width and of substantially the same cross section as the other portions of the arms. A portion of the recess in the central cross bar opening into the lower open slot 24 may also cooperate with a passage communicating between the open slot 24 and a button loop 25 extending outwardly in the lower bar 19, the passage being of sufficient width to permit the shank 25a of a button to pass therethrough into the loop. The width of the recess of the central bar is sufficient to provide head room for the button as it passes through the open slot with the shank thereof extending into the button loop. The shank 25a of the button may, of course, be

fastened to an article to be supported such as an overall bib 25^b.

The recess in the central bar 19 opening into the lower slot besides forming desired flexibility in the torsion arms 22 and 23 and providing head room for the insertion of the head of a button, also permits of the formation of a resilient cushion by the strap in extending thereacross. This resilient cushion prevents accidental dis- 10 placement of the button from the button loop although it permits ready engagement of the button into the button loop and disengagement therefrom when the button is manually urged against the cushion. The strap is held across 15 the recess by the comparative narrowness of the lower open slot, the width of the slot being substantially the same as the thickness of the material of the average strap.

The upper cross bar 17 may preferably be provided with an offset portion 26 at a central portion of the width thereof adjacent the subtending tongue and extending in a direction away therefrom to facilitate the introduction of the free end of the strap through the slot formed 25 between the tongue 20 and the cross bar 17 which it subtends.

In threading the buckle just described, a corner of the strap may be introduced into the opening produced by the offset portion 26 of the bar 30 17 and behind the tongue 18 and thereafter pulled through the slot between the tongue and its subtended bar 17, the resiliency of the central cross bar 18 permitting movement of the gripping portion 20 away from the top bar. The normal position of the gripping portion or tongue 20, with respect to the top cross bar 17 which it 35 subtends before a strap is threaded therethrough, is not pertinent and may vary from actual contact therebetween to a spaced distance of approximately the thickness of a strap or greater, since the gripping of the strap is accommodated by the exertion of a relative pull between the strap and frame. However, due to manufacturing expediencies, it is desirable to have a close 40 adjustment between the gripping portion and the subtended cross bar.

The free end of the strap extending from the upper slot is thereafter threaded through the lower slot 24 preferably by inserting a corner of the end of the strap in the central enlarged portion of the lower slot, whereafter it may readily be pulled so that its entire width lies within the slot with the end extending downwardly. Upon exertion of a relative pull between the strap and the frame, that is, the buckle being held at its lower end by the button of the garment to be supported and the strap being urged in a direction away therefrom, the arms 22 and 23 are placed under torsional strain and institute movement of the gripping portion 20 in a direction toward the top bar to grip the strap in the upper slot. An adjustment of the strap is readily had by pulling the strap at an intermediate portion within the buckle frame in a direction opposite to that above recited so that the tongue 20 is moved in a direction away from the top bar to relieve the gripping engagement of the strap. After the necessary adjustment, the free end of the strap is thereafter pulled taut in the lower slot and upon an insertion of a relative pull between the strap and the frame, as first stated, a gripping occurs to prevent a displacement from the adjusted position.

The strap 20^a is normally of substantially the same width as the distance between the inside

of the side bars 15 and 16. Ordinarily the strap 20^a is greater in thickness at the side edges thereof, their being in some instances a double thickness on the one edge and four thicknesses on the opposite edge, or in some conditions, four thicknesses on one edge and twice as many on the other edge. In speaking, therefore, of the thickness of the strap, it is to be understood that the thickness is determined by the several folded layers constituting the strap. In some instances the tongue 21 may extend to engage the folded and sewed edges of the strap although in other instances the tongue may be of shorter width and may not engage these folded edges. In any event, due to the desired flexibility of the central cross bar, the gripping portion thereof will accommodate an uneven thickness of the strap. The full width of the strap is such as to extend beyond the ends of the tongue to occupy the space of the slot defined by the top bar and the arms 20 22 at the juncture thereof with the side bars, the above-indicated short projecting portions of the arms 22 acting as stops. These short projecting portions limit and guide the sidewise movement of the strap and prevents the material thereof from working around the ends of the tongue. Further, the tongue 20 is preferably provided with sharp end portions at the juncture of the ends with the gripping edge thereof which also cooperate with the stops to prevent the goods 30 from sidewise movement should the buckle become tilted and a sidewise pull of the strap occur.

The loop 25 is preferably provided with offset portions 27 extending forwardly or upwardly with reference to the remainder of the face of the loop and portions 28 of the cross bar 19 are offset in the opposite direction to extend rearwardly of the loop for facilitating the entrance of the button into the loop, the forwardly extending offset portions 27 directing the button forwardly over the cross bar 18 when tension is released from the strap thereby preventing displacement of the button from the loop.

The arms 22 and 23 at the portions thereof 45 adjacent the lower cross bar 19, which are in effect the torsion arms supporting the gripping member, are of particular significance in that they back up the cloth which is forming one side of the button opening. The fact that the cloth 50 can be pushed back between these two arms and further that the arms themselves yield, makes for easy manual engagement and disengagement of the button and prevents accidental disengagement of the button.

In the development of the buckle of this invention, a novel relationship of spring properties and thickness of material has been adopted. It has been found that if a buckle of the above type is formed to accommodate a strap of from 1 1/2" to 2" in width, the material may be .028" to .016" in thickness, the Rockwell hardness being held between 25 and 55 on the "C" scale with a 150 kilogram load. In the case of buckles accommodating straps of between 1 1/2" and 1 7/8" in width, the thickness range of the material of the buckle ranges between .024" and .012" with the Rockwell hardness remaining the same.

The buckle is preferably fabricated out of dead soft sheet metal and, as above described, very thin material and the high physical properties are secured after the forming operations have been performed by thermal heat treatment. The cool 70 upkeep cost is tremendously lower than in the usual fabrication methods where relatively hard 75

materials are fabricated. Also, an increase in speed of production because of a lesser number of shut-downs and lesser number of tool sharpening operations and the like is to be had. A more detailed discussion of the physical properties of the buckle of the present invention may be had by reference to an application which will hereafter be filed as a continuation of the present application.

Referring now more particularly to Figs. 6 to 8, inclusive, a construction very much similar to that previously recited is illustrated in which the side bars 29 and 30 are connected by three cross bars 31, 32 and 33. The buckle is likewise formed of a single piece of sheet metal, the central bar being formed from the material within the frame and having a tongue 34 and arms 35 and 36 oppositely extending from the tongue to be resiliently secured to the side bars 29 and 30, the tongue subtending in close proximity a major portion of the upper cross bar 31 thereby forming a strap gripping slot. The arms 35 and 36 at their points of attachment to the side bars are spaced from the upper cross bar a distance slightly greater than the average thickness of the strap, the arms being tortuous in the direction of their length and narrow in width to meet at the lower end of the tongue. The arms 35 and 36 cooperate with the lower bar 33 to form an open lower slot and the material of the arms adjacent the lower slot is recessed preferably at 31 to provide head room for the insertion of the head of a button against the resilient cushion of the strap extending across the recess and in the slot. The shank of the button may pass into a passageway 38 extending between the lower open slot and the button loop 39 extending outwardly from the lower cross bar 33. The passageway 38 is sufficiently wide to accommodate the shank of the button so that the button may be inserted through the open slot adjacent the lower bar 33 of the buckle.

The tongue 34 and the upper cross bar 31 overlap each other for at least a portion of their subtending areas as by means of the tongue being provided with extruded portions 40. The upper surface of the button loop 39 is provided with offset portions 41 extending upwardly and the lower bar 33 is provided with offset portions 42 extending in an opposite direction to facilitate introduction of the button into the loop, the offset portions 41 directing the button over the resilient central cross bar 32 to prevent accidental displacement of the button from the button loop. With reference to the particular modification just described, the cross bar is formed of flat metal and is not, therefore, of arcuate cross section as in the previously described embodiment. Further, the central cross bar 32 is not provided with a recess opening into the lower open slot, but is merely recessed interiorly of a portion of the tongue as at 32a to provide added flexibility to the cross bar so that, as in the case of the previously described embodiment, the gripping portion of the central cross bar may function satisfactorily to grip the strap whether or not uneven thicknesses in the width of the material of the strap are presented.

Referring now more particularly to Figs. 9 and 10, a modified form of buckle is shown comprising side bars 42 and 43 connected by three spaced cross bars 44, 45 and 46. The central cross bar 45 comprises oppositely extending arms 47 and 48 resiliently secured to the side bars and extend-

ing from a gripping portion 49 that subtends in close proximity a major portion of the top bar 44 to form an upper slot through which a strap may be threaded and gripped. The arms 47 and 48 form an open lower slot adjacent the lower bar 46 for receiving the free end of the strap, the arms 47 and 48 being tortuous in the direction of their length, narrow in width and preferably arcuate in cross section to resiliently secure the central cross bar to the side bars 42 and 43.

In this embodiment, the gripping portion 49 is shown as being flat while the supporting arms 47 and 48 are of arcuate cross section. The gripping portion 49 and the upper cross bar 44 overlap each other for at least a portion of their subtended areas in a manner, for example, such as by extruding a portion of the material of the tongue 49 as at 50. In this embodiment the gripping portion or tongue 49 is offset outwardly at a portion centrally of its width to facilitate the entrance of a corner of the free end of the strap in threading the strap through the buckle as distinguished from the previously described embodiment where the upper cross bar was offset to facilitate the introduction of a corner of the strap.

The central cross bar 45 is preferably recessed opposite an outwardly extending portion of the lower cross bar 46, this outwardly extending portion forming a button loop 51 having a passageway therefrom opening into the elongated open slot in which the free end of the strap is received. The recessed portion on the central bar provides head room for the passing of the button as the shank of the button engages in the button loop, the head of the button acting against a resilient cushion in the form of the strap extending across the recessed portion.

Referring now more particularly to Figs. 11 to 14 of the drawing, a still further embodiment of this invention is shown comprising a frame formed of side bars 52 and 53 connected by three spaced bars 54, 55 and 56. The central bar is very much similar to the central cross bar in Fig. 1 with the exception that the gripping portion 57 thereof is made to overlap the cross bar 54 which it subtends by forcing the central cross bar out of its normal stamped position, as shown in Fig. 11, to the operative position as shown in Fig. 13. Further, the central bar 55 is preferably disposed in the same plane as the face of the frame of the buckle and the overlapping cooperating cross bar 54 of the frame is displaced rearwardly to accommodate the central cross bar as at 58 and limits the movement of the cross bar in one direction. It is further shown that the central cross bar 55 may be prevented from movement beyond its elastic limits in the other direction by means of cooperating pairs of lips 59 and 60 which overlap and are disposed in such relation as to permit movement of the gripping portion within the desired limits, whereafter lip 59, supported close to the frame and having little if any resiliency, prevents the movement of the flexible tongue by contacting with the lip 60 thereon in the direction of movement thereof outwardly from the frame.

While several embodiments of this invention are herein shown and described, it is to be understood that various modifications thereof may be apparent to those skilled in the art without departing from the spirit and scope of this invention, and, therefore, this invention is to be limited only by the claims.

ited solely by the scope of the prior art and the appended claims.

We claim:

1. A buckle formed of a single piece of sheet metal constituting a frame which comprises side bars and three spaced cross bars connecting said side bars, the central bar being resiliently secured to the said side bars and being provided with a gripping portion that subtends in close proximity a major portion of the top bar to form an upper slot through which a strap may be threaded and gripped and to form an open lower slot adjacent the lower bar for receiving the free end of the strap, a portion of said central bar having a recess providing lateral arms extending between said recess and said lower slot, said recess being defined by said gripping portion and said arms, said recess and said lower slot communicating to provide a flexibility of said central bar for accommodating a strap of varying thickness across the width thereof whereby upon the exertion of a relative pull between said strap and said frame the gripping portion of said central bar is moved toward and away from said top bar to grip uniformly said strap threaded in said upper slot.

2. A buckle formed of a single sheet of metal constituting a frame which comprises side bars and cross bars connecting said side bars in which a central bar is disposed between upper and lower bars, the central bar being resiliently secured to the said side bars and being provided with a gripping portion that subtends in close proximity a major portion of the top bar to form an upper slot through which a strap may be threaded and gripped and to form an open lower slot adjacent the lower bar for receiving the free end of the strap, said central bar and said upper bar overlapping for at least a portion of their subtended areas for limiting the movement of said resiliently secured bar in one direction, and means cooperating with said central bar for limiting the movement thereof in the other direction, a portion of said central bar adjacent said gripping portion having a recess providing lateral arms extending between said recess and said lower slot, said recess and said lower slot communicating to provide a flexibility of said central bar for accommodating a strap of varying thickness across the width thereof whereby upon the exertion of a relative pull between said strap and said frame the gripping portion of said central bar is moved toward and away from said top bar to grip uniformly said strap threaded in said upper slot.

3. A buckle formed of a single piece of sheet metal constituting a frame which comprises side bars and three spaced cross bars connecting said side bars, the central bar being resiliently secured to said side bars and being provided with a gripping portion that subtends in close proximity a major portion of the top bar to form an upper slot through which a strap is threaded and gripped and to form an open lower slot adjacent the lower bar for receiving the free end of the strap, said lower bar having an outwardly extending button loop with a passage leading to said lower slot for receiving a button, said passage being of sufficient width only to permit the shank of the button to pass therethrough into said loop, said lower slot and said central bar cooperating to permit passage of the head of the button into and out of said loop whereby the central bar may or may not be moved out of the plane of the buckle in accordance with the thickness of the strap, a portion of said central bar being placed

under torsional strain upon the exertion of a relative pull between said strap and said frame to permit movement of said gripping portion in a direction toward and away from said top bar to grip said strap threaded in said upper slot.

4. A buckle formed of a single piece of sheet metal constituting a frame which comprises side bars and three spaced cross bars connecting said side bars, the central bar being resiliently secured to said side bars and being provided with a gripping portion that subtends in close proximity a major portion of the top bar to form an upper slot through which a strap is threaded and gripped and to form an open lower slot adjacent the lower bar for receiving the free end of the strap, said lower bar having an outwardly extending button loop with a passage leading to said lower slot for receiving a button, said passage being of sufficient width only to permit the shank of the button to pass therethrough into said loop, said central bar being recessed to provide head room for the passage of the button into and out of the loop and being resilient whereby it may or may not be moved out of the plane of the buckle in accordance with the thickness of the strap, a portion of said central bar being placed under torsional strain upon the exertion of a relative pull between said strap and said frame to permit movement of said gripping portion in a direction toward and away from said top bar to grip said strap threaded in said upper slot.

5. A buckle formed of a single piece of sheet metal constituting a frame having side bars and three spaced cross bars connecting said side bars, the central cross bar having a tongue constituting a strap gripping portion that subtends and lies closely adjacent to a major portion of the upper cross bar and having resilient arms extending from said side bars toward each other for cooperation with the lower cross bar to form an open lower slot for receiving the free end of a strap, said lower cross bar having an outwardly extending button loop provided with a passage leading to said open slot for receiving a button acting to support a garment or other article and said passage being of sufficient width to permit the shank of said button only to pass therethrough into said loop, said arms cooperating with said lower slot to permit passage of the head of the button into and out of the loop and terminating inwardly a spaced distance from each other opposite said button loop and being extended in a direction away from each other to join said tongue portion, said arms being resilient whereby they may or may not be moved out of the plane of the frame in accordance with the thickness of the strap and whereby upon the exertion of a relative pull between said strap and said frame they are placed under torsional strain to permit movement of said tongue portion in a direction toward and away from the cooperating upper cross bar to grip said strap threaded between the upper cross bar and said tongue.

6. A buckle formed of a single piece of sheet metal constituting a frame having side bars and three spaced cross bars connecting said side bars, the central cross bar being provided with a tongue and arms oppositely extending from said tongue to resiliently secure said central cross bar to said side bars, said tongue having a substantially straight edge subtending and lying closely adjacent to a major portion of the upper cross bar thereby forming a strap gripping slot extending substantially beyond the ends of said tongue to

accommodate that portion of the strap extending beyond the tongue, the juncture of the ends and gripping edge of said tongue being sharp to prevent sidewise movement of the strap, said 5 arms being tortuous in the direction of their length and forming an open slot with said lower cross bar for receiving the free end of said strap and said arms upon the exertion of a relative pull between said strap and said frame being 10 subjected to torsional strain to institute movement of said tongue in a direction toward and away from the cooperating cross bar to grip said strap threaded therebetween.

7. A buckle for use with a strap formed of a 15 single piece of sheet metal constituting a frame having side bars and three spaced cross bars connecting said side bars, the central cross bar being provided with a tongue and arms oppositely extending from said tongue to resiliently secure 20 said central cross bar to said side bars, a gripping portion of said tongue subtending and lying closely adjacent to a major portion of the upper cross bar thereby forming a strap gripping slot 15 and the points at which said arms are attached to said side bars being spaced from said upper cross bar a distance such that the cross-section of said strap at said gripping slot will be maintained in substantially a straight plane, said arms 25 being extended substantially to said gripping portion and being thereafter tortuous in the direction of their length, narrow in width and forming an open slot with said lower cross bar for receiving the free end of said strap and said 30 arms upon the exertion of a relative pull between said strap and said frame being subjected to torsional strain to institute movement of said tongue in a direction toward and away from the cooperating upper cross bar to grip said strap threaded therebetween.

and said frame being subjected to torsional strain to institute movement of said tongue in a direction toward and away from the cooperating upper cross bar to grip said strap threaded therebetween.

5

8. A buckle for use with a strap formed of a single piece of sheet metal constituting a frame having side bars and three spaced cross bars connecting said side bars, the central cross bar being provided with a tongue and arms oppositely extending from said tongue to resiliently secure 10 said central cross bar to said side bars, a gripping portion of said tongue subtending and lying closely adjacent to a major portion of the upper cross bar thereby forming a strap gripping slot 15 and the points at which said arms are attached to said side bars being spaced from said upper cross bar a distance such that the cross-section of said strap at said gripping slot will be maintained in substantially a straight plane, said arms 20 being extended substantially to said gripping portion and being thereafter tortuous in the direction of their length, narrow in width and forming an open slot with said lower cross bar for receiving the free end of said strap and said 25 arms upon the exertion of a relative pull between said strap and said frame being subjected to torsional strain to institute movement of said tongue in a direction toward and away from the cooperating upper cross bar to grip said strap 30 threaded therebetween.
